UNITED STATES PATENT OFFICE.

GEORGE B. EVANS, OF NEWTON, MASSACHUSETTS.

DELIVERING MECHANISM.

1,243,723.

Specification of Letters Patent. Patented Oct. 23, 1917.

Application filed May 3, 1917. Serial No. 166,154.

To all whom it may concern:

Be it known that I, GEORGE B. EVANS, a citizen of the United States, residing at Newton, in the county of Middlesex and State of Massachusetts, have invented new and useful Improvements in Delivering Mechanism, of which the following is a specification.

The present invention relates to a machine or device for delivering a given number of articles such as nails, for instance, or any other articles of similar nature such as tacks, screws, rivets, etc., which are capable of being placed in and guided by a raceway, and have heads which are exposed and may be acted upon by the separating or measuring element of the mechanism in order to separate those articles which are delivered at any one time from other articles which are retained for a subsequent delivery. Inasmuch as the machine is designed to deliver a given number of the articles or pieces at each operation it may be aptly called a counting mechanism. In order to illustrate the invention I have shown a specific embodiment of the same adapted to deliver given quantities or numbers of nails into a container, such as an envelop, whereby the exact number of nails required to attach some particular article to a mounting, such for example as a rubber heel to a shoe, may be counted off and delivered in connection with the article to be fastened. Such nails are adapted to be supported in an inclined raceway by their heads, which rest on the ledges bounding the raceway, the shanks of the nails being suspended through the slot between such ledges; and the separating element or member, by which a given quantity of nails is counted off and separated from the balance of the nails, is arranged to act in conjunction with the exposed heads of the nails thus arranged.

It is to be understood that I do not limit the invention to an apparatus for acting upon nails only, but intend to use it for counting off and delivering articles of any sort which have heads so formed as to support the articles in the manner indicated in or on a raceway. Therefore the illustration of the invention in a nail-delivering apparatus, and the use of the term "nails" in the following specification to designate the articles delivered thereby, are to be understood as being for illustration only, and not to indicate any other limitation of the invention as to its construction or mode of use, or the purpose for which its is used, than appears from the express terms of the appended claims.

The invention consists of the novel elements and features hereinafter particularly described and pointed out in the claims, to which reference is now directed in connection with the drawings.

Figure 1 shows a side elevation of one form of my invention adapted to be used for the delivery of nails.

Fig. 2 is a front elevation of the same as seen from the left of Fig. 1.

Fig. 3 is a plain view.

Figs. 4, 5, and 6 each shows a longitudinal central section of the device and illustrate the measuring or counting, and nail-releasing elements of the device in different positions.

Fig. 7 is a side elevation of a modification of the invention.

Fig. 8 is a longitudinal central section of the same modification illustrating the parts thereof in a different position from that shown in Fig. 7.

The same reference characters indicate the same parts in all the figures.

Referring first to Figs. 1 to 6 inclusive, 11 represents the frame of an inclined raceway which is provided with ledges 12 and 13 arranged in parallel with a slot or passageway 14 between them. This is a conventional illustration of such raceway as is common in nailing machines. I do not claim as any part of my invention any improvement or modification in the raceway itself, wherefore any type or form of raceway heretofore used may be employed for this element of my apparatus. Indeed it may be considered that the raceway here shown is the nail-delivering part of any standard nailing machine. Such machines are ordinarily provided with a hopper of some sort containing the nails and by which the same are lifted automatically and placed properly in the raceway so as to hang by their heads on the ledges 12 and 13 with their shanks passing through the slot 14. As hoppers, nail-lifters and other devices for feeding nails into and properly placing them in a raceway are common and well known, I have not deemed it necessary to show any form of such appliance in these drawings. It is sufficient for my purpose that it be

understood that nails are placed by some agency in the manner indicated in the raceway and that they are fed by gravity, owing to the inclination of the raceway, to the delivery end thereof.

- 5 At the end of the raceway is a spout 15 which is adapted to be entered into the mouth of a container, preferably such as an envelop, in which the given quantity of nails are placed 10 to provide a package for convenience of vending to the user. A bridge 16 is provided over the spout to hold open the mouth of the envelop while the nails are being discharged thereinto, the position of the envelop when 15 receiving the nails being indicated by broken lines at 17 in Fig. 8. This part also is no part of my invention but is illustrative merely of a guide for conducting the delivered nails to the receiver. It is attached in any convenient way at the end of the raceway below 20 that part thereof which supports and guides the nails. A guard 18 is located below the path in which the nails travel and extends from the raceway end into the spout, its 25 purpose being to overlie certain operating parts hereinafter described and prevent the delivered nails from falling upon the same or from being arrested on their way to the spout.
- 30 At the end of the raceway is a gate 19 which normally closes the end of the slot 14. It is provided with guideways 20 (Figs. 2 and 3) which contain ribs 21 which are mounted upon or attached to the raceway 35 frame in any convenient manner and are arranged so that the gate may slide up and down between the extreme positions shown in Fig. 4 and in Fig. 6 respectively, in one of which it closes the passage of the raceway, 40 and in the other of which it is raised above the raceway far enough to permit the nails to pass under it. Said gate is formed as the upper transverse member of a substantially rectangular frame which has side members 22, 22 and a transverse bottom member 23 embracing a central vertically elongated opening 24. The side members 22 of this frame are the parts which contain the guide grooves 20 and are engaged with the guiding ribs. A lever 25 is pivoted to the raceway frame on a stud 26, and extends over and bears upon the upper side of the member 23. This lever has a short arm or finger 27 which is engaged with one end of the 45 spring 28, the other end of which is attached to the raceway frame. The function of the spring 28 is to hold the gate in its lowered position, shown in Fig. 4, wherein it closes the end of the raceway, said spring 50 being capable of yielding when superior force is applied to raise the gate.

The frame which carries or forms part of the gate has wings 29 at each side which bear upon arms 30, 31 fixed to a rock shaft 32 mounted in a bearing in the raceway

frame and extending to opposite sides of the same. The arm 30 is provided with an extension 33 having a guide portion 34 on which is adjustably mounted a stop 35, said stop being in the form of a finger having a 70 slotted body 36 which embraces the guide 34 and is provided with a set screw 37 adapted to exert pressure against the guide and thereby to clamp the finger in any one of numerous positions of adjustment. If desired the arm 31 may be like the arm 30, that is having a similar extension and guide, and the stop 35 formed as a bar mounted at both ends on the two arms, instead of as a finger supported at one end only, but it is sufficient for the purpose here illustrated that the stop be supported at one end only as shown. On the other hand the reason for providing two wings 29 and two arms is to cause the application of forces applied 80 through the same to the rock shaft 32 to act symmetrically on opposite sides of the bearing of the latter, so that when the shaft is rocked by movement of the gate, as hereinafter described, the shaft will remain in 85 the desired relation with its axis extending always in the same direction. In other words the forces thus applied will not have any tendency to tilt the shaft in any direction, whether up and down or forward and 90 back. The stop 35, or that portion thereof which overlies the slot in the raceway, is formed with a narrow edge 38 adjacent to the line in which the nail heads lie. Springs 39 and 40 are connected to the arms 30, 31 95 respectively and to the raceway frame. The point in connection 41 of these springs with the arms is above the rock shaft, and the springs are otherwise located and under such stress as to exert force away from the 100 adjacent raceway end, that is, to the right with respect to the illustration in the drawings. These springs, however, are light and weak as compared with the spring 28.

The bearing for the rock shaft 32 is 110 wider than the rock shaft, as is clearly shown in the sectional views and is indicated by dotted lines in Fig. 1. The simplest form of this bearing is a hole 42 in the raceway frame through which the shaft passes, said 115 hole being widened on one side in such manner that its major diameter extends preferably on a slant downward toward the delivery end of the raceway. This feature of the bearing has a function in connection 120 with the disparity in power between the spring 28 and the springs 39 and 40, which will presently be described and explained.

In the embodiment shown in Figs. 1 to 6 125 the spout 15 is mounted directly on the frame which includes the gate, and is used to operate the gate. Thus the operator, in delivering a number of nails into an envelop, places the envelop over the end of the spout, and raises the latter, thus raising the gate. 130

The motion thus produced acts against the force exerted by spring 28, which yields. The raising of the gate frame also raises the wings 29 which bear on the extremities of the arms 30 and 31 and normally hold the arm extension 33 raised so that the stop 35 is above the line of nail heads in the position shown in Fig. 4. The first part of the gate frame movement partially relieves the arms of the pressure applied thereto by the wings 29, allowing said arms to be turned by the action of the light springs 39 and 40 until the stop 38 arrives in the position shown in Fig. 5, when it rests on the head of one of the nails, and its weight is supported thereby. This point is reached before the gate has risen high enough to release the nails immediately back of it. The further rise of the gate to the position shown in Fig. 6 removes the pressure of the wings 29 entirely from the arms 30, 31, leaving the latter and the connecting rock shaft free to be moved bodily. The springs 39 and 40 now shift these members as far as permitted by the excess in width of the bearing 42 over the diameter of the rock shaft 32, thereby shifting the rock shaft from the forward side to the rear side of the bearing, as illustrated by comparison of Figs. 5 and 6. This movement causes a rearward shifting of the stop 35, whereby it passes from the position where it first engaged the head of one nail, to a position close to the forward edge of the head of the next nail. Thereby the stop is positioned to hold back all of the nails lying in back of it, and not to arrest any of the nails in front of its knife edge 38. Thus when the gate rises clear of the raceway, all of the nails in front of the stop are released and are allowed to slide forward until they fall into the spout and are guided thereby into the envelop or other container 17. In falling from the forward end of the raceway the nails strike the guard strip 18 and are guided thereby over the lever 25 and the bottom member 23 of the gate frame so that they do not strike and are not caught by or between these parts and the raceway frame.

When the charge of nails has been delivered and the envelop removed from the spout, the release of the latter permits the spring 28 to return the gate into the closed position. Before reaching this position the wings 29 engage the arms 30, 31 and, in the remainder of the movement of the gate frame, swing the arms downward and raise the stop 35, at the same time shifting the arms and the rock shaft 32 forward to the forward limit of the bearing 42.

The modification shown in Figs. 7 and 8 differs from that above described in this particular only, that the spout is secured to the raceway frame, and the movement of the gate is effected by a bell crank lever hav-

ing a handle portion 43 and a jaw portion 44 which embraces the bottom member of the gate frame. This lever is provided with a finger 45 to which a spring 46, corresponding to the spring 28, is connected, and it also has a stop finger 47 adapted to bear against part of the raceway frame and limit the movement given to the lever by said spring. This lever 43, 44 performs exactly the same function as the lever 25, with the additional function of serving as a means for elevating the gate and thereby operating the delivery apparatus. In all other respects this form of the apparatus is identical with that previously described, and the same reference characters are applied to the corresponding parts.

A feature of particular value and utility in both illustrated forms of the invention, and one which I particularly claim, is the provision of means for causing or permitting a rearward movement bodily of the stop after the same has first come into engagement with one of the nails. The reason and purpose for such movement is this. Headed fastenings such as nails always occupy a position in an inclined raceway with their heads overlapping, as indicated in the drawings. When a number of pieces, more than one, are required to be delivered at one time, and particularly provision for adjustment is required whereby any number within limits may be thus delivered, it is necessary that the separator or stop which counts off the number of pieces to be delivered from those withheld should be over the raceway and capable of entering between the exposed parts of adjacent pieces, that is between the exposed heads thereof. Now on account of the overlapping relation of these heads it is impossible by means of a simple motion to bring a stop or separator between the adjacent nails in such a manner that it will in all cases, without regard to the number of nails counted off, and without fail, cause to be delivered exactly the correct designated number. The feature which I am now explaining assures the delivery of the correct number always without fail, whatever that number may be, by reason of the compound movement which is given to it. The first movement of the stop is into the position shown in Fig. 5, and takes place more or less abruptly toward the line of the raceway in front of the foremost nail of the group of nails to be withheld. But in order that it may be in front of this nail it must be directly over the last nail of the group to be delivered, and in any case can not be more than a very short distance back of the center of that nail. Thus if the movement of the stop should cease at this point, it would bear on the nail and would be liable to hold it so that it would not be delivered; yet it could not be depended upon to hold

this nail under all circumstances, wherefore there would be an uncertainty as to the number of nails delivered. Assuming that the stop were set to deliver seven nails by coming down in front of the eighth nail on the raceway, then sometimes it would deliver seven nails and sometimes only six. The second component of motion of the stop, which takes place when the stop arms and 10 rock shaft are all moved rearwardly at once, shifts the edge of the stop from nearly over the center of the nail with which it engages to a position directly in front of the next nail and therefore almost clear of the nail 15 over which it lay at first, or at least over no more than the extreme back edge of the head, where it will not have any effect in holding back that nail. At the same time that the stop is thus carried backward, it 20 is also brought nearer to the plane of the raceway, and so near that it will not permit the nail in back of it to pass beneath it.

An abutment 48 is provided on the side of the raceway under the arm extension 33 25 and limits the movement of the latter so that the stop need not actually come into contact with the raceway.

The adjustment provided for the stop 35 enables the same to be set to deliver any 30 number of nails from two up to the limit imposed by the length of the extension 33, and the peculiar manner of movement of the stop insures that it will deliver exactly the same number at every operation as long as 35 it is retained in one setting. This is the principal advantage of my machine, that it will deliver the same number of pieces at every operation. I do not limit the invention to the precise means herein shown and 40 described for providing the peculiar character of motion to the stop which makes this result possible, as the details of the various parts may be modified in various ways. Thus I include within the scope of protection 45 which I claim herein, any means of mounting and operating the stop, or the equivalent of the stop, whereby to produce a combination of movements thereof first toward the raceway over the head of a nail 50 and then backward toward the next nail to the rear.

The terms hereinbefore used indicating relative positions are used descriptively and without limiting significance otherwise than 55 as the use of a gravity feed raceway imparts a special significance to words indicating relation or difference of height. In particular the words "front" and "back" and words of like import have been used without intention 60 of limiting the invention in any wise to the particular embodiment here shown. In using these terms the end of the raceway from which the nails are delivered is considered the front end and the terms have therefore 65 only this significance.

What I claim and desire to secure by Letters Patent is:

1. An apparatus for delivering a specified number of articles comprising a guideway on which such articles are arranged in line, 70 a gate for arresting the endmost article of such line, a stop normally at one side of such line but adapted to be advanced so as to arrest one of the articles at a distance from the end of the line, and means for giving 75 movements to said stop in the direction first toward the line of articles and then in a direction away from the front end of such line.

2. A delivering mechanism comprising a raceway, a gate at the end of said raceway 80 mounted so as to be shifted between the position wherein it covers the discharge end of the raceway and a position in which it uncovers such end, a stop mounted over the raceway, an arm carrying said stop, the arm 85 and gate having interengaging portions by which the stop is withdrawn from the raceway when the gate is closed, and a yielding means for shifting the stop toward the raceway when the gate is open.

3. A delivering mechanism comprising a raceway, a gate at the end of said raceway mounted so as to be shifted between the position wherein it covers the discharge end of the raceway and a position in which it uncovers such end, a stop mounted over the raceway, an arm carrying said stop, the arm 95 and gate having interengaging portions by which the stop is withdrawn from the raceway when the gate is closed, a resilient 100 means for shifting the stop toward the raceway when the gate is open, and a spring arranged to exert force on said gate tending to close the same, said spring being of greater power than said resilient means.

4. The combination with a raceway adapted to support the heads of nails and similar headed pieces, a gate arranged adjacent to the end of said raceway movable into positions wherein it respectively closes and opens 110 the outlet from the raceway, a spring arranged to exert force on said gate tending to close the same, an arm pivoted beside the raceway having an extension, a stop carried by said extension and overlying the raceway 115 so that the articles traveling along the raceway pass under the same, said gate and arm having interengaging portions arranged to cause displacement of said stop from the raceway when the gate is closed and a light 120 spring arranged to apply force to said arm tending so to move the same that the stop is brought toward the raceway.

5. The combination of a raceway adapted to receive the shanks of nails and to support the heads thereof, a gate arranged across the end of said raceway and being removable so as to uncover such end, an arm mounted adjacent to the raceway, a stop carried by said arm and extending over the 130

raceway, said arm being movable both pivotally and also bodily toward and away from the raceway end, and the stop being arranged so that the pivotal motion of said arm causes it to approach and recede from the nail-supporting part of the raceway respectively, said gate and arm having inter-engaging portions arranged to cause movement of the arm toward the raceway end 10 and displacement of the stop from the nail-supporting part of the raceway when the gate is closed, and yielding means for causing opposite pivotal and translatory movements of the arm when the gate is opened.

15 6. A nail-delivering mechanism comprising a raceway having ledges to support the heads of nails and a slot to receive the shanks of such nails, an arm pivotally mounted beside the raceway and being movable bodily with respect to its pivotal axis toward and away from the raceway end, a stop carried by said arm and being movable by the oscillations thereof toward and away from said raceway ledges, a gate normally 20 covering the end of the raceway and having a part engaged with a part of said arm holding the latter advanced toward the end of the raceway and the stop withdrawn from the raceway ledges, said gate being shift- 25 able into a position where it uncovers the

raceway end to permit discharge of nails therefrom, and the engaging portions of the gate and arm being then disengaged, and a spring arranged to exert force on said arm tending also to withdraw the same from the 35 raceway end and to turn it so that the stop is brought toward the raceway ledges.

7. A nail-delivering apparatus comprising an inclined raceway having ledges for supporting the heads, and a slot for receiving the shanks, of nails, a vertically movable gate arranged in front of the lower end of said raceway and across the slot to arrest the nails in the raceway, an arm pivotally mounted at one side of the raceway, 40 a stop carried by the arm overlying the raceway, said gate having a wing engaging the arm and holding the same so that the stop is elevated when the gate is closed, said gate being adapted to be raised so as to release the nails and being thereby caused to release the arm, and a spring acting on said arm tending to turn the same so that the stop is brought toward the raceway edges, the pivot axis of said arm being also shift- 45 able at the same time away from the raceway end.

In testimony whereof I have affixed my signature.

GEORGE B. EVANS.
